COLOSTOMY PAD

Frank H. Frissell, Middletown, Conn.

Application January 22, 1936, Serial No. 60,229

3 Claims. (Cl. 128—283)

My invention relates to an improvement in colostomy pads, the object being to produce at a relatively low cost for manufacture, a pad of superior convenience and effectiveness, as well as long life.

With these ends in view, my invention consists in a colostomy pad comprising a concavo-convex body of sponge rubber having a thin, impermeable, flexible skin or film covering its inner 10 face and a supporting backing applied to its outer face.

My invention further consists in a colostomy pad comprising a concavo-convex body of sponge rubber having a thin, impermeable, flexible skin 15 covering its inner face and having a supporting backing applied to its outer face, the edges of the said skin extending outwardly over the edges of the said concavo-convex sponge-rubber body and joining the edges of the said backing to seal 20 in the said body.

My invention further consists in a colostomy pad characterized as above and having certain details of construction as will hereinafter be described and pointed out in the claims.

25 In the accompanying drawing:

Fig. 1 shows my improved pad applied to a figure;

Fig. 2 is a view in front elevation of an abdominal belt shown as open for the removal or introduction of the pad, which is illustrated as in place, but, for convenience of illustration, shown without any paper or other napkin;

Fig. 3 is a view in elevation of the belt as extended;

35 Fig. 4 is a detached view of one form which my improved pad may assume; and

Fig. 5 is a view thereof in transverse section on the line 5—5 of Fig. 4.

My improved pad 9 as herein shown consists 40 of a concavo-convex oval body 10 of sponge rubber of sufficient thickness so that when compressed by the pressure of the expelled fecal matter, it creates what may be termed a temporary fecal-pocket, which is indicated by the broken line 11, 45 the edges of the said body being, as shown, tapered or thinned. The inner face of the said body, including its tapered or thinned edges, is entirely covered by a thin, impermeable, flexible rubber skin 12, while its outer face is substantially covered by a relatively-rigid, impermeable, hard-rubber backing 13, the edges of which are tapered from the center outward in all directions and fall just short of the tapered edges of the concavo-convex sponge-rubber body 10. The tapered edges of the body 10 are also covered by the

skin 14, which projects beyond them and is turned outward and over to meet the tapered edges of the hard-rubber backing 13 so that the sponge-rubber body is everywhere enclosed and sealed in and so protected against its penetration by 5 any fluids. The particular shape or outline of the pad as a unit may be varied according to circumstances.

In use, a relatively-large napkin or towel of soft paper, such as crepe paper, or cloth, or 10 equivalent material 22 is placed over the colostomy and against the person's skin. The pad is then placed directly over the towel and hence over the colostomy and held firmly in place by pressure applied to the outer face of its hard-rubber outer backing by means of a suitable 15 abdominal belt, which securely prevents it from moving in either direction after having been applied. As shown in Fig. 1, the towel 22 extends above and below the edges of the belt. The belt 20 itself may be of any approved construction. As shown, it consists of a relatively-wide two-part band 15 stiffened with bones 16 and provided with snap-fasteners 17 of the ordinary button type, located at its respective ends. The two half- 25 sections of the band are united by lacings 18 providing for the adjustability of the belt. The ends of the lacings 18 are secured in the usual manner to belt-straps 19 and 20, one of which is provided with an ordinary buckle 21. To open the belt, 30 the strap is unbuckled and the fastenings 17 are pulled apart for the introduction or removal of the pad and towel. The edges of the pad are thus pressed firmly against the body of the wearer and held in place under the required pressure by means of tightening the belt in the usual manner. When the belt is tightened as described, the thinned edges of the pad are so firmly pressed against the towel and hence upon the skin of the wearer that no air or gas or fluids can escape. 35

In the operation of the belt, when fecal matter is ejected against the towel 22 covering the skin 12 of the concavo-convex sponge body 10, the same is compressed as indicated by the broken line 11 to form a fecal-pocket, which is lined, as it were, by the towel which receives the fecal matter. To remove the pad, it is only necessary to loosen and separate the belt-straps 19 and 20, after which the button-fasteners are disengaged, 45 as shown in Fig. 2, sufficiently to permit the removal, by its gathered edges, of the towel containing the fecal matter, in most cases without so much as staining the pad proper. The skin is now cleansed if necessary, another towel is placed 50 55

in position and the pad replaced and anchored in position by the belt, as described.

My improved pad, on account of its peculiar construction, is very light and convenient to handle and its adaptation to form in itself a fecal pocket under the pressure of fecal matter makes it very efficient as a surgical bandage.

I have described the supporting backing of the sponge-rubber body of the pad as made of hard rubber or equivalent material. Thus, I may find it feasible to use light metal or pressed paper or any impermeable composition of sufficient rigidity to hold the sponge-rubber body in shape, in place of a hard-rubber backing.

15 1. I claim:

1. A colostomy pad comprising a concavo-convex body of sponge rubber having a thin, impermeable, flexible skin or film covering its inner face and an impermeable supporting backing applied to its outer face.

2. A colostomy pad comprising a concavo-

convex body of sponge rubber having a thin, impermeable, flexible skin or film covering its inner face and an impermeable supporting backing covering its outer face, the projecting edges of the said skin being lapped over the outer edges of the sponge-rubber body to prevent the access of air or of liquids thereinto.

3. A colostomy pad comprising a concavo-convex body of sponge rubber, the edges of which are tapered or thinned, a thin impermeable skin or film covering the inner face of said concavo-convex body, and a hard-rubber backing applied to the outer face of the said body for supporting the same and having its edges thinned and stopped short of the tapered edges of the body, the said skin being lapped outwardly over the tapered edges of the sponge body and joined to the tapered edges of the rubber backing so as to exclude air or liquids from the said body.

20
